UNITED STATES PATENT OFFICE.

GOTTLOB BINDER, OF PHILADELPHIA, PENNSYLVANIA.

IRONING-MACHINE.

SPECIFICATION forming part of Letters Patent No. 444,722, dated January 13, 1891.

Application filed March 9, 1889. Serial No. 302,615. (No model.)

To all whom it may concern:

Be it known that I, GOTTLB BINDER, a citizen of the United States, and a resident of Philadelphia, Pennsylvania, have invented 5 certain Improvements in Ironing-Machines, of which the following is a specification.

My invention relates to that class of ironing-machines in which a rotating iron is moved in the arc of a circle over a suitably-shaped table; and it consists of certain improvements in the devices employed for moving said iron, together with other details of construction, as more fully described herein-after.

15 In the accompanying drawings, Figure 1 is a sectional elevation on the line 1 2, Fig. 2, of a machine constructed in accordance with my invention. Fig. 2 is a front view of the machine. Fig. 3 is a portion of the machine 20 corresponding with Fig. 1, with the parts in different positions. Fig. 4 is a perspective view, partially in section, of the ironing-table and its connections; and Fig. 5 is a view of a modified form of the machine.

25 The frame-work of the machine consists of two suitably-shaped standards A, connected to each other by suitable stay-rods and by a cross-bar B. Secured to the bar B is a bracket C, supporting in suitable bearings in

30 its upper end a transverse rock-shaft e. The ironing-table D has an arm D', extending rearwardly to the shaft c in the upper end of the bracket C, and is firmly secured to said shaft, as shown in Fig. 1, the shaft c thus

35 forming a pivot for the movement of the table, the vertical movement of the table, however, being limited in one direction by the iron and in the other direction by a stop c', attached to the arm D', and the stop c', attached to the bracket C, the stop c' on the arm D' coming in contact with the stop c' on the bracket C when the table is on its lowest 40 position. To the under side of the arm D' of the table is pivoted a bar d², extending from the pivot to a point directly under the front of the table, and being there connected to a treadle d by an adjustable rod d'. The table D when not under the iron is supported by a spring g, extending from the supporting-bar d²; but as this spring is not in itself sufficient to withstand the downward pressure of 45 the iron I provide the supporting-bar with

an upward extension or filling block d³, through which the pressure of the iron is transmitted to the bar d². This construction, 55 by which the entire body of the ironing-board is left free, is very desirable in many cases, as it is sometimes necessary to place a portion of the article being ironed under the board, and such an article may be readily 60 placed in position by allowing the supporting-bar d² to drop, the spring g then forcing the board away from the supporting-bracket.

A strip e, of felt or equivalent material, is secured to the upper edge of the block d³ and 65 prevents the soiling or cutting of any article of clothing which it may be necessary to place between the board and the block.

I prefer making the rod d' adjustable, so that the pressure exerted upon the table by 70 the iron may be varied. The rod in this instance is formed of two portions e' e², the portion e' being provided with a swiveled nut e³, turning on the threaded end of the portion e² and shortening or lengthening the rod, as de- 75 sired.

The iron I is in the form of a hollow cylinder, tapering at each end and having shanks adapted to bearings at the upper ends of arms E, pivoted at their lower ends upon a shaft g' 80 supported in the frame-work.

I prefer to introduce a mixture of air and gas into the iron through pipes F, which communicate with a burner f, extending the entire length of the working-face of the iron, 85 the products of combustion escaping at the opposite end, or, if desired, steam may be introduced into the iron for the same purpose.

The shaft g', which forms the pivot-point for the arm E E, is provided with a loose 90 double-faced pulley g², one face of which is connected to a pulley i on the shank of the iron I by a belt g³. The pulley g² is driven from the main driving-shaft J through the medium of a belt j', and the driving-pulley 95 for the iron being at the pivot-point of the arms carrying the iron the iron will be turned evenly and regularly, and no matter what position (with respect to the perpendicular) the arms may assume the belt is at all times taut. 100

For the purpose of giving to the iron a reciprocating motion over the board I pivot to each of the arms E a friction-bar H, which may be placed in contact with a constantly-

rotating friction-wheel h on a shaft H' , driven from the shaft J by a pinion j and a spur-wheel k . These friction-bars rest upon anti-friction wheels m , carried by arms D' , secured 5 to the shaft c , an arm D' , forming part of the pivoted frame of the ironing-table, being also secured to said shaft, so that when the table is raised by the depression of the pedal d the anti-friction wheels m are also raised and the 10 friction-bars H are forced against the constantly-rotating friction-wheels h , resulting in the forward movement of the iron over the table.

It is of course desirable for evenness of 15 working that each arm E should be provided with a pivoted friction-bar H ; but the machine may be constructed, if desired, with but one arm and one operating friction-disk placed at either side of the machine, as will be readily understood. To bring the iron back to its 20 normal position, I may employ springs s , the ends of which are connected, respectively, to the frame and the arms E ; or, if desired, a weighted lever w , keyed to the shaft g' , may 25 be used, as shown by dotted lines in Fig. 1.

For the purpose of clamping the work to the board I employ a clamp-plate p on the small arm of the bell-crank lever Q , pivoted at q to the arm D' of the ironing-board, as 30 will be seen on reference to Fig. 4. The longer arm of this lever is connected at its lower end with a pedal lever r by means of a link t , and the clamp-plate is held down on the board by spring t' , attached to the long arm of the lever and to the bar B . The clamp-plate of 35 the machine, when used for ironing shirts, is made semicircular in form and adapted to fit over the neckband of the shirt and hold it in position. In addition to the clamping-plate, 40 I employ small flexible rollers q' , mounted on brackets q^2 , projecting from the arms E and adapted to press against the sides of the ironing-table as the said frame reciprocates, the rollers acting to press to the sides of the table 45 any material projecting over its edges.

In ironing open-front shirts it has been found difficult to place a shirt evenly and smoothly upon a board of the ordinary construction where such a board is secured to a 50 supporting-bracket, and great care must be taken to avoid any wrinkles or twisting of the article. With the construction of board I use, however, the back of the shirt may be placed under the board and only the front 55 portion brought on top, as there is sufficient space between the filling-block d^3 and the board D to allow for the insertion of the back of the shirt.

In the construction of the machine shown 60 in Fig. 5 the table is pivoted to the bracket C in the same manner as before; but in this case the iron-carrying arms E are each provided with two friction-bars H^* , one bar causing the movement of the table in one direction and the other bar returning it to the first position. The arms D^2* , secured to the shaft c , are provided with anti-friction wheels

m , which control the contact of the bars H^* with the constantly-rotated friction-wheel h , the upper bar normally resting loosely on the 70 friction-wheel h , the weight of the bars, however, being insufficient to effect any movement of the table until the movement of the table presses the upper friction-wheel m against its bar with sufficient force to permit 75 the rotating friction-wheel h to act, and a reciprocating motion is given to the iron, the direction of movement of the iron depending upon which of the friction-bars is placed in contact with the driving-disk. If, for instance, the table is moved by its pedal up into contact with the iron, the upper friction-bar is pressed into contact with the driving-disk and the iron and its frame are pushed forward. When the table is lowered, however, 85 the lower anti-friction wheel raises its bar into contact with the driving-disk and the table is moved back.

In Fig. 5 the ironing-table is down, and the lower bar is consequently in driving contact 90 with the friction-disk, the iron being moved in the direction indicated by the arrow. In this construction, however, the friction-disk is rotated in a direction opposite to that shown in Figs. 1, 2, and 3, a pinion l being interposed between the toothed wheels j and k for the purpose of producing the desired change in the direction of the motion.

It will be understood that in the construction of machine shown and described in Figs. 100 1, 2, 3, and 4 toothed racks may be substituted for the friction-bars H and toothed wheels gearing with said racks used in place of the friction-disk h .

I claim as my invention—

1. In an ironing-machine, the combination 105 of the table, an iron adapted to move over the same, a carrying-frame for said iron with bars attached to said frame, and rotating disks with which said bars are moved into contact upon the raising of said ironing-table for the purpose of reciprocating said iron, substantially as described.

2. The combination, in an ironing-machine, 115 of the ironing-table pivotally supported at its inner end by a rock-shaft, a reciprocating iron, and its carrying-frame with mechanism for reciprocating said carrying-frame, consisting of friction-bars attached to said frame, arms secured to the rock-shaft, anti-friction wheels 120 m , carried by said arms, and constantly-rotating friction-disks with which said bars are adapted to be moved into contact, substantially as specified.

3. The combination, in an ironing-machine, 125 of an iron, means for reciprocating the same, a table pivotally supported at its inner end, and a bracket hinged to said table and adapted to support the same during the action of the iron with mechanism for raising said bracket 130 into contact with the table, substantially as specified.

4. The combination, in an ironing-machine, 135 of a table D , a supporting-arm D' therefor, a

clamp-plate pivoted thereto, a lever Q, connected to said clamp-plate, a bell-crank treadle-lever having one of its arms connected to the long arm of said lever, and a spring t' , adapted to keep said clamp-plate in close contact with the board, substantially as set forth.

5. The combination, in an ironing-machine, with a rotated iron and its reciprocated carrying-frame, of a curved table pivoted at one end to the frame at a point to the rear of the pivot-point of the iron-carrying frame, a supporting-bar d^2 , pivoted at its rear end to the

table, a foot-lever d , and a bar d' , connecting said foot-lever to the front end of the supporting-bar for the purpose of lifting said 15 table into contact with the iron, substantially as specified.

In testimony whereof I have signed my name to this specification in the presence of two subscribing witnesses.

GOTTLOB BINDER.
